UNITED STATES PATENT OFFICE.

GEORGE P. DAVIS, OF DETROIT, ASSIGNOR TO THE ORIEL CABINET COMPANY, OF GRAND RAPIDS, MICHIGAN.

BRACKET FOR DESKS.

SPECIFICATION forming part of Letters Patent No. 408,087, dated July 30, 1889.

Application filed January 31, 1889. Serial No. 298,292. (No model.)

To all whom it may concern:

Be it known that I, GEORGE P. DAVIS, of Detroit, in the county of Wayne and State of Michigan, have invented a new and useful Improvement in Brackets for Desks, of which the following is a specification.

My invention consists in an improvement in brackets for desks, hereinafter fully described and claimed.

10 Figure 1 is an end elevation of the desk; Fig. 2, a front elevation of part of the desk; Fig. 3, a front elevation of the bracket; Fig. 4, a detail view, and Fig. 5 a side elevation of the bracket.

15 X represents a desk of any style or shape, having a hinged lid L, which closes the front of the desk when in the position shown in full lines, Fig. 1, and forms a writing-table when turned down, as shown in dotted lines,

20 Fig. 1. The ordinary way of supporting the lid when turned down is by sliding arms which pull out under the lid; and the object of my invention is to provide a bracket to support the lid, which is operated without attention, merely by the act of raising or lowering the lid.

25 B represents a piece of metal simulating one leaf of a hinge, which is secured to the lid L. C represents a longer piece of metal, 30 which also simulates the leaf of a hinge, and the parts B and C are pivoted together at A. The front end of the part or leaf C is bent down and inward, ending in a T-shaped piece of metal D.

35 E represents a plate of metal having therein

a slot F, in which the lower end of leaf C plays freely, and having at its upper end a cross-slot G, through which the T-shaped end D of leaf C may be introduced, so that the part D will lie behind the plate E. The 40 metal plate E is secured to the front of the desk in line with the bracket B C, and a slot is formed in the desk back of said plate to permit free movement of the part D therein, as shown in dotted lines in Fig. 1. 45

The operation of my invention is as follows: When the lid L is raised, as in Fig. 2 and in full lines in Fig. 1, the bracket B C appears to be a hinge, though of course the real hinges which connect the lid L to the desk are concealed. When the lid L is turned down, the part C of the bracket swings on its pivot A, and its free end passes downward in slot F until it reaches the bottom of said slot, when its further motion is arrested and it serves as 50 a bracket to support the lid L. 55

What I claim as my invention, and desire to secure by Letters Patent, is—

In combination with the desk X, having the inclined lid L, the hinge-bracket B C, 60 jointed at A, the part B, fastened to the lid L, the part C, bent around the lower edge of said lid and terminating in a T-shaped end D, and the slotted plate E, substantially as shown and described.

GEO. P. DAVIS.
